E. S. SMITH,
DETACHABLE LINK,
APPLICATION FILED MAR. 30, 1914.

1,121,770.

Patented Dec. 22, 1914.

UNITED STATES PATENT OFFICE.

EZRA S. SMITH, OF ATTLEBORO, MASSACHUSETTS, ASSIGNOR TO R. F. SIMMONS COMPANY, A CORPORATION OF RHODE ISLAND.

DETACHABLE LINK.

1,121,770.

Specification of Letters Patent. Patented Dec. 22, 1914.

Application filed March 30, 1914. Serial No. 828,164.

To all whom it may concern:

Be it known that I, EZRA S. SMITH, a citizen of the United States, residing at Attleboro, in the county of Bristol and State of Massachusetts, have invented certain new and useful Improvements in Detachable Links, of which the following is a specification.

My invention relates to detachable links for expandible bracelets, and has for its essential objects the provision in this class of chain bracelets of means for rendering an apparently endless chain or circlet separable or disconnected at some point in the circlet; to render the attaching and detaching means inconspicuous, and to insure a maximum of strength of structure, and facility and effectiveness of operation. It has been sought to effect these ends by cutting away a portion of the exposed front face of a link, which has resulted in an unsightly appearance and marring of the structure; and this attempt has always been accompanied by the requirement of the insertion of some small auxiliary link, which besides involving an increase of expense, broke the regular contour of the bracelet body, and detracted from the expansion of the bracelet.

Further objects of this invention are to specifically overcome the enumerated disadvantages.

In the accompanying drawings which form a part of this specification, Figures 1 and 2 are plan and front elevations respectively of a bracelet embodying my invention, Figs. 3 and 4, enlarged front elevations of the connecting portion of the same in closed and open positions respectively, Fig. 5, an enlarged section of the connecting portion on line *w*, *w*, of Fig. 2, Fig. 6, a section on line *w*, *w*, of Fig. 5, Figs. 7 and 8, enlarged sections of the connecting portion in open position taken on lines *w*, *w*, of Fig. 2, and *w*, *w*, of Fig. 5 respectively, and Figs. 9 and 10 transverse sections taken on lines *y*, *y*, and *z*, *z*, of Fig. 8.

Like reference characters indicate like parts throughout the views.

The bracelet comprises in series a plurality of intermediate links *A* slidably embraced by lateral links *B*. The links *A* are longitudinally curved and have integral with or fixed to one end laterally extending guides *a*. The links *B* are alternately disposed

with relation to the central links *A* which they embrace, and constitute frames. In detail each frame *B* comprises parallel shells *b* comprising marginal internal flanges *b'*; said shells being connected near their ends by posts *C* attached by solder or otherwise. Helical springs *D* are located between the post of one link, and the inner end of the central link.

All the links of the bracelet are of the construction already described with the exception of one central link and one lateral link, which exceptional links or units will now be described. A central link *A'* is provided which is similar to the links *A* except that the former is somewhat longer. Fixed by solder to or integral with the link *A'* along the major portion of its open sides are lateral plates *b*² of substantially the same form and dimensions as the plates *b*, and provided with the inturned flanges *b*³. The plates *b*² complete a link portion *B'* which has the appearance of the links *B*, although their fixed relation with the intermediate member *A'* constitutes in reality a single link closed upon all sides except that a resultant opening occurs through each end of the link *A'* as at *d*, due to the shorter length of the plates *b*² relatively to the length of the member *A'*. Through these open portions *d* through each end of the described link pass the posts *C* of the adjacent links.

The described closed link *B'* is transversely severed so as to divide the link *B'* into a section *E* and a section *F*. The former comprises oppositely disposed central lugs *e*, and the section *F* is provided with oppositely disposed central rectangular cavities *f* in which the lugs or projections *e* are adapted to closely fit. Connecting the lugs *e* is a cross-piece loop or post *g* through which passes a hook *h*, whose shank *H* is fixed by solder or otherwise to the inner face of one of the plates *b*² of the section *F*. The opposite plate *b*² of the section *E* is provided with an opening *I* through which loosely passes the thumb piece *i* fixed to the face of the spring *j* which has one end attached by solder or otherwise as at *k* to the inner face of the shell *b*² of the section *E*.

It will be observed that in closed position the parts of the link *B'*, as shown in Figs. 3, 5, and 6, are in close contact with each

other, the lugs *e* registering in the cavities *f*, and the spring and the beak or hook *h* of the resilient member *H* pressing against the spring *j*, with its end abutting against a shoulder *l* upon the fixed portion of the spring *j*. In order to detach the parts the thumb piece *i* is depressed, bringing the tongue *h* out of contact with the shoulder *l*, and the sections *E* and *F* are drawn apart into the positions shown in Figs. 4, 7, and 8, with the hook engaging merely the loop *g*. The tongue *h* of the hook may then be readily withdrawn from the cross-piece *g*, and the parts be thus entirely separated. This form of bracelet is therefore capable of being applied to wrists of various sizes without being strained by passing over a large hand. It will be observed that the thumb piece *i* is the only exposed irregularity upon the face of the bracelet, and that this member is located upon a side of the bracelet, and not upon the face of the same. The absence of any auxiliary link between the closed link *B'* and the adjacent links *B* renders the contour of the bracelet symmetrical, proportionately increases the resiliency of the elements, and decreases the cost of manufacture.

What I claim is,—

- 30 1. A detachable link of the type set forth, comprising two transversely separable sections comprising central walls and side walls, one of said side walls being provided with a perforation, a spring upon the perforated wall and provided with an abutment, a thumb piece upon the spring extending through the perforation, and a resilient hook fixed in the non-perforated section adapted to engage said abutment.
- 40 2. A detachable link of the type set forth, comprising two transversely separable closed housing sections, one section being provided with a perforation, a transversely disposed cross-piece in the open end of the perforated section, a flat spring fixed at one end in the perforated section, a shoulder on the fixed portion of the spring, a thumb piece on the spring extending through the perforation, and a hook fixed in the second section adapted to extend into the perforation.

rated section around the loop in contact with the spring and to abut against the shoulder.

3. A detachable link of the type set forth, comprising two transversely separable closed housing sections, one of said sections being provided with a perforation, lugs upon the perforated section, a cross-piece connecting the lugs, a spring in said section having a return portion forming a shoulder, a thumb piece on the spring extending into the perforation, the second section being provided with slots to receive the lugs, and a hook in the second section adapted to extend into the first section around the cross-piece and to rest upon said spring with its free end extended toward and in contact with the end of the return portion of said spring.

4. A detachable link of the type set forth, comprising two transversely separable closed housing sections, one of said sections being provided with a perforation, lugs upon the perforated section, a spring in said section, a thumb piece on the spring extending into the perforation, the second section being provided with slots to receive the lugs, and a hook in the second section in contact with the spring when the link is closed, the free ends of said hook and spring being extended in opposite directions.

5. A detachable link of the type set forth, comprising two transversely separable closed housing sections, lugs upon one section, a spring fixed in said section, the second section being provided with slots to receive the lugs, and a hook in the second section engaging the spring, the free ends of said hook and spring being extended in opposite directions and the free end of the hook overlapping the free end of the spring and engaging a shoulder on the latter when the link is in closed position.

In testimony whereof I have affixed my signature in presence of two witnesses.

EZRA S. SMITH.
